UNITED STATES PATENT OFFICE.

ERNEST C. BLACKWELL, OF ROCHESTER, NEW HAMPSHIRE, ASSIGNOR TO SPAULDING FIBRE COMPANY, INC., OF ROCHESTER, NEW HAMPSHIRE, A CORPORATION OF NEW HAMPSHIRE.

METHOD OF MOLDING COUNTERS.

Original application filed June 2, 1926, Serial No. 113,140. Divided and this application filed May 23, 1927. Serial No. 193,448.

This invention relates to a method of making manufactured counters for boots and shoes. The invention is especially useful in, but is not restricted to, the manufacture of 5 molded counters that are designed to give support to the longitudinal arch of the foot of the wearer of the shoe into which they are built.

The novel wing-type counter produced by 10 the method hereinafter described is disclosed and claimed in applicant's co-pending application for Letters Patent of the United States Serial No. 113,140, filed June 2, 1926 from which this present application is a 15 division.

While counters for fitting the heel part of 20 the last have been molded by machinery for many years perfection has not yet been attained in the production of counters of such length at the inner side as to form a forward wing which overlaps, in greater or less degree, the concavity of the last at the inside shank or below the instep of the wearer of 25 the shoe. Those skilled in the art well understand the difficulties encountered in attempting to last an upper along the inside shank of the shoe when the upper is reinforced by a stiff, substantially flat counter wing. If the upper, because of the presence 30 beneath it of an unmolded or only partially molded counter wing, cannot be conformed to the shape of the last at the instep, then the completed shoe will bulge out or otherwise be distorted at this highly important 35 part of the shoe and will not exhibit to view the true style of the last which has been designed with great care. Furthermore the shoemaker cannot even be sure that the two shoes of a single pair will be alike after lasting. Such a shoe, especially if worn by 40 those troubled with pes planus or "flat foot" which requires for its relief a firm support of the longitudinal arch of the foot, will add discomfort rather than comfort because 45 the bulge maintained at the instep by the improperly lasted overlapping counter wing does not permit the shoe to hug the foot at the instep but gives an undesirable looseness at this point.

50 The object of the present invention is to improve the manufacture of molded counters in such manner as to produce counters of the

type having a forward wing that will be free from the defects and disadvantages just described, i. e. such a degree of perfection will 55 be attained in the molding thereof that there will be no necessity of a material manipulation of the instep portion of the counter, during the lasting operation, to bring it into its final and desired relation to the lines of 60 the instep of the last which it overlaps.

To the accomplishment of this object a practice of the method hereinafter set forth produces a counter of the type having a forward wing, at the inside at least, characterized by a form and shape imparted to it during the process of its manufacture that will snugly fit the contour of the last which it embraces and more especially closely hug the surface of the last at the inside shank during 70 the further processes of making the shoe. Skilled shoemakers will recognize that a counter of the type described having the characteristics defined will add quality, accuracy and perfection to shoemaking as at 75 present practised, because its use will overcome all irregularity and lack of uniformity heretofore present in shoes of the same size or style into which wing-type counters are built, due to the heretofore present necessity 80 of shaping the forwardly projecting portions of such counters, to some extent at least, during the lasting operation.

Accordingly the present invention consists in the method of making counters, the preferred manner of practising which is hereinafter described and then defined in its true scope in the appended claims.

An understanding of the method will be assisted by reference to the accompanying 90 drawings, in which:

Figure 1 is a view, in plan, of a blank for a counter adapted to both men's and women's shoes; Fig. 2 is a view, in perspective, of a counter molded from the blank of Fig. 1 in 95 a manner to fit the heel end of the last and provide a heel-seat flange; Fig. 3 is a view, in perspective, of the counter of Fig. 2 after the final step in the process of manufacture has been performed, namely, shaping the forward wing at the inside to exactly fit the contour of the last to which it is later to be applied; Fig. 4 is a view, in side elevation, of the counter of Fig. 3 illustrating the po-

sition of the counter when built into a shoe. The counter illustrated by Figs. 2 to 4 is for a right shoe and the point of view is from the outer side of the shoe; Fig. 5 is a view, in plan and on a smaller scale, of a blank for a counter adapted to women's pumps; and Fig. 6 is a view, in perspective, of a molded counter for women's pumps embodying the novel feature of the present 10 invention.

In the embodiment of the invention illustrated in Figs. 1 to 4 of the drawing a counter blank 2 of a material having the required strength to receive the molding pressure and 15 to thereafter retain its molded shape without reinforcement, is produced by dinking to a contour which will provide, when bent for introduction to a counter molding machine, a forwardly extending inner wing of 20 such length as to overlap a portion, at least, of the instep of the last. The material of which the counter of the present invention has been formed is known commercially as fibre and is a manufactured product but a 25 practice of the process is not limited to any particular material. The composition of this material is well known, and after the shredded fibre which forms the body of the composition and other ingredients of the 30 formula have been thoroughly mixed into a consistent mass, this mass is sheeted, compressed to the desired thickness and after drying becomes fibre board. This fibre board is dinked to the desired shape for wing 35 type counters and the blank is usually provided with a mark or nick 3 to indicate the center of the heel and is then skived on one face or the other in accordance with the desire of the shoe manufacturer. The figures 40 of the drawing all illustrate counters for a right shoe so that in the blank of Fig. 1 the portion 4, to the left of the mark 3, will form the outer side of the molded counter and the longer portion 6, to the right of the mark 3, 45 will form the inner side thereof.

The first operation in the process of manufacture of a molded counter from the skived blank 2 is to pass the blank through rollers shaped to cup the blank slightly forming 50 what is known as a "clam shell". This crimping or rolling operation, while not essential, shapes the blank slightly for fitting better within the heel part molds of a counter-molding machine of the type illustrated 55 in Letters Patent of the United States No. 1,138,123, granted May 4, 1915 to Roswell A. Lancey. The next operation comprises bending the two sides 4 and 6 toward each other about the mark 3 as a central point 60 and placing the bent counter on the preferably hot center mold block of the machine whereupon this mold block is moved upward between the two preferably hot side mold blocks which simultaneously close inward 65 upon the blank. It will be under-

stood that the blank is tempered before pressure is applied and that the mold blocks are interchangeable for molding counters to fit all sizes and styles of lasts. The depth of the mold block is less than the depth of the counter and the second manufacturing step by the machine comprises wiping the projecting lower margin of the counter inward against the face of the inner mold block to form a heel-seat flange 8. The counter at 75 this stage of its manufacture is illustrated by Fig. 2, and it will be observed that while the heel portion has been finally shaped and the heel-seat flange 8 is perfectly formed along the lower margin of the outer side 4 80 and at the center, it is imperfectly formed along the inner side 6. The heel-seat flange along the lower margin of the inner side 6 merges into the substantially straight, lower edge 9 of the forward or instep wing 10 85 produced, in this instance, by the elongated or extended inner side of the counter. The partially completed counter, illustrated by Fig. 2, is then completed by an additional molding step which is concerned solely with 90 the portion of the counter which produces the instep overlapping wing 10 at the forward end of the inner side 6 of the molded heel portion.

This final or wing molding operation is 95 preferably, but not necessarily, performed in another specially designed counter-molding machine which comprises essentially a mold block having a molding face shaped like the contour of the inside shank of the 100 last, for the particular size and style of the shoe in which the counter is to be used, and a complementary mold block. Such support is given to the partially completed counter of Fig. 2 as will enable the forward wing 105 10 to be held between the two molds in such manner that it can be molded thereby into the form, and position relatively to the heel end of the counter, that it must have in the completed shoe if it is to perform its proper 110 function and add quality and perfection to shoemaking. Thereupon the two mold blocks are brought together, one at the inside and the other at the outside of the wing 10 115 which is still in temper, and the pressure is maintained long enough to permit the fibre of the molded wing to set and permanently hold its new position, shape and form.

After the second molding operation the counter has the form of Figs. 3 and 4. 120 The heel-seat flange 8 is perfectly formed throughout the entire lower edge of the heel end of the counter, both the side and end portions lying in substantially the same plane (see Fig. 3); but the contour of the 125 last at the inside shank that has been permanently impressed into the forward wing 10, has flared this wing both outwardly and downwardly relatively to the plane of the heel-seat flange 8 (see Fig. 4) thus providing 130

for an accurate fit of the counter to the inside shank of the last and for a merging of said flange into the lower margin of the wing 10 without the distortion present in 5 the partially completed counter of Fig. 2.

The final result of the counter-forming operations described is to produce a molded counter that, when assembled on the last between the lining and upper, will lie 10 snugly against the last and will hug the margin of the insole so closely that the lasting and sewing operations may both be performed without having to manipulate 15 or change the original assembly position of the molded wing 10 which is effective for accomplishing its function of preserving the lines of the shoe and perfecting its fit.

The manufacture of a wing-type molded counter for women's pumps is conducted 20 under an exactly similar process as that just described, except that the blank is differently shaped providing an extended wing at the inner side of considerably less length due both to the smaller sizes of the shoes and to 25 the popular short vamp. The preferred shape of counter blank for a woman's pump is illustrated by Fig. 5. The blank 12 has an outer side 14 substantially as long as the inner side 16 and the forward or instep 30 wing 18 is correspondingly shorter than the same wing 10 on the counter blank 2, but nevertheless is ample to receive the second molding and thus enable the shoe upper readily to be drawn to the lines of the last 35 and cause it to snugly fit the instep of the wearer of the shoe.

Attention is called to the shape of the counter blank illustrated in Figs. 1 and 5. It will be observed that the lower edge of 40 the wing portion forms a straight continuation of the edge along which the heel-seat flange 8 is to be formed. Heretofore, in the manufacture of wing-type counters having a substantially unmolded wing it was 45 considered desirable to add material, in the form of a bulge along the end portion of said lower edge opposite the inner wing portion 6 or 16 in order to aid the laster in drawing the inner wing to a position under 50 the instep portion of the last, or to cause the counter wing to apparently have this position when not drawn snugly to the contour of the instep portion of the last which it overlaps. When the inner wing portion is 55 properly molded according to the teaching of this invention, on assembly of the molded counter and last the inner wing has such a perfect relation, without further shaping by lasting, to the portion of the instep of the 60 last which it overlaps that the requirement of a bulging inner edge is obviated and, in fact, would be a detriment by providing an excess of counter material at this point. The present method has, therefore, the added 65 advantage of saving stock in that more

counter blanks having a straight lower edge may be dinked from a sheet of material of a given size.

When the method of manufacture as hereinbefore described is practised there results 70 a pre-formed counter, of the type having an inner wing that extends forwardly sufficiently to overlap the inside shank of the last, that can be lasted without the necessity of 75 materially altering its form or position, and when sewed to the insole will permanently preserve the style lines of the shoe at the inside shank that originate in the design of the last on which the shoe is built. The type 80 of counter described has the further function, when molded throughout its entire surface in accordance with the teaching of this invention, of providing in the shoe an instep support of such contour and permanency as to give material aid to the support 85 of weakened longitudinal arches and consequent relief to those suffering from flat foot.

Having thus described the novel method and one mode of practising it when employing 90 its underlying principle, yet recognizing that some modifications and changes may be made without departing from its spirit and scope, what is claimed as new, 95 is:—

1. The method of making counters which includes the steps of molding a counter blank to fit the heel end of a last in a manner to provide an instep wing on the inside, forming a heel-seat flange, and thereafter molding the instep wing to fit the contour of the inside shank of the last.

2. The method of making counters which includes the steps of shaping a counter blank, of the type having an inner side 105 long enough to overlap the inside shank of the last, to fit the heel end of a last, forming a heel-seat flange while leaving the lower margin of the forward end of said inner side as a substantially straight extension 110 of the heel-seat flange at that side, and finally setting the forward end of said inner side both downwardly and outwardly relatively to the plane of said heel-seat flange.

3. The method of making counters which 115 comprises molding a counter blank in a manner to fit the heel end of a last and provide an inner side having a forward wing adapted to overlap the instep portion of the last, forming a heel-seat flange, and molding the forward wing of said inner side to a shape and form which will cause it to extend under the instep portion of the last at 120 said inner side and substantially fit the contour of the surface thereof which it overlaps.

4. The method of making counters which 125 comprises molding the heel portion, of a counter blank having an instep wing at the inner side of said heel portion, to the de- 130

- sired shape, and thereafter applying pressure to both sides of said instep wing by means of a mold block inside of the wing having a molding face shaped like the contour of the inside shank of the last and a mold block outside of the wing having a molding face complementary to the molding face of said mold block inside of the wing.
5. The method of making counters which 10 comprises producing a blank shaped to provide a forwardly extending wing at at least one side of the heel portion thereof, molding the heel portion of said blank to fit the heel end of a last while leaving the forwardly 15 extending wing portion incompletely molded, and completing the counter by molding the incompletely wing portion to substantially the contour of the shank portion of the last which it is adapted to overlap.
- 10 6. The method of making counters which comprises producing a blank shaped to provide a heel portion and also an inner wing portion of such length as to overlap the instep portion of the last, completely molding 20 said heel portion to fit the heel end of the
- last while only partially molding said instep wing, and then, as a separate operation, completing the molding of the wing to fit said instep portion of the last.
7. The method of making counters which 30 comprises producing a blank having one straight edge and one curved edge and of sufficient length to embrace the heel end of the last and to overlap the instep portion of the last, molding one portion of said 35 blank to fit the heel end of the last, and thereafter molding the remaining portion of said blank in a manner to flare it outwardly relatively to the molded heel part to cause said straight edge to follow the 40 line of the last bottom at the instep.
8. That step in the method of making molded counters of the type having a forwardly extending wing which consists in pressing the wing between molds shaped to 45 impress into said wing the contour of the shank portion of the last which said wing will overlap.

ERNEST C. BLACKWELL.
